(76) Inventor: **Zohar Haykeen**, Valley Village, CA
(US)

* cited by examiner

(**) Term: **14 Years**

(21) Appl. No.: **29/402,659**

Primary Examiner — Antoine D Davis

(74) Attorney, Agent, or Firm — Thomas I. Rozsa

(22) Filed: **Sep. 26, 2011**

(57) **CLAIM**

I claim the ornamental design for a wall mountable height measuring device, as shown and described.

(51) **LOC (9) Cl.** 10-04

DESCRIPTION

(52) **U.S. Cl.** D10/70

(58) **Field of Classification Search** D10/70;
33/511, 512, 515, 832, 838, 483, 484, 485,
33/492, 783, 806, 809-812

FIG. 1 is a side perspective view of a wall mountable height measuring device;

See application file for complete search history.

FIG. 2 is a front view of FIG. 1;

(56) **References Cited**

FIG. 3 is a rear view of FIG. 1;

FIG. 4 is a side view of FIG. 1;

FIG. 5 is a top perspective view of FIG. 1; and,
FIG. 6 is a bottom perspective view of FIG. 1.
